UNITED STATES PATENT OFFICE.

ROBERT A. BOSWELL, OF WASHINGTON, DISTRICT OF COLUMBIA.

PRINTING OR POSTMARKING MACHINE.

1,243,802.

Specification of Letters Patent. Patented Oct. 23, 1917.

Application filed September 16, 1913. Serial No. 790,083.

To all whom it may concern:

Be it known that I, ROBERT A. BOSWELL, a citizen of the United States of America, residing at Washington city, District of Columbia, have invented new and useful Printing or Postmarking Machines, of which the following is a specification.

This invention pertains to printing machines in general and to post-marking and stamp-canceling machines in particular. Primarily, it is a machine designed to increase the range of mechanisms in its class and to that end is provided with devices that will accomplish this result most effectively. Whether post-marking machines are constructed with intermittently operated printing hubs or continuously rotating printing cylinders, it has heretofore been found necessary to provide some device in the path of the letter with which the letter may co-act to effect the printing operation.

These devices which project into the letter path possess the inherent fault of tearing the edges of matter to be printed upon unless they are most sensitively constructed, this liability to disfigurement increasing as the thickness of the mail or other matter diminishes.

In the machine on which it is desired to obtain Letters Patent, an intermittently operated printing member is employed, but the letters encounter no sort of mechanical device in their transit, simply passing between a series of rolls where the necessary printing operations are effected by means of various electrical connections and disconnections that will be hereinafter described.

The elimination of the mechanical letter tripped device obviously extends the usefulness of the machine, and, at such times as it is not engaged in the cancellation of mail, it may be used for the printing of what is known in post office parlance as facing slips.

The drawing illustrates what at present seems to be the most satisfactory arrangement of parts, but the inventor realizes that, in the practical application of his device, certain changes and alterations may suggest themselves and these he reserves the right to make, if by so doing he does not depart from the spirit of his invention or deviate from his annexed claims.

In the drawings which accompany this application and form a part thereof:—

Figure 1 is a plan view of a machine showing the application of the invention

and the position of the various parts when no mail is being canceled.

Fig. 2 is a similar plan showing the series of operations that ensue after a letter or card passes between the supplementary feed rolls.

Fig. 3 is a perspective view of the main release magnet.

Fig. 4 is a perspective view of the contact block and its attendant blow-out magnet.

Fig. 5 is a perspective view of the detaining cam.

Fig. 6 is a longitudinal elevation of the auxiliary contact magnet.

Fig. 7 is a transverse elevation of the same magnet.

Fig. 8 is a perspective view of the auxiliary contact magnet showing clearly the shape of the arm and horns.

Fig. 9 is a section on the line *a*—*a* Fig. 1.

Fig. 10 is a section on the line *b*—*b* of Fig. 1.

Fig. 11 is a plan view of the printing mechanism showing a different form of actuating means.

Fig. 12 is a sectional view on line *c*—*c* of Fig. 11.

Fig. 13 is another modification of the principles involved; an electric generator taking the place of the battery 103 as the current supplying means.

Fig. 14 is a section on the line *x*—*y* of Fig. 13, looking in the direction of the arrows.

Fig. 15 shows the same parts illustrated in Fig. 14 (the clutch 122 being eliminated) and is intended to show the position of the trip lever and its attendant links at the moment of liberating the driven member of the clutch.

Referring to the drawings,

1 is a bed plate which is divided into a feeding portion, *a*, a printing portion *b* and a stacking portion *c*. Below 1 is a similar bed plate 2 and these two bed plates are connected by any suitable mechanical means to form a compartment for housing those parts of the machine which are not necessarily exposed. Above 1 is mounted the feed roller 3 secured to the shaft 4 and having the rubber-bound periphery 5. Adjacent to 3 is the feed chute formed by the fences 6 and 7, while opposite to 3 may be mounted any conventional form of separator, which, in this case, is a rubber-covered roll 8 secured firmly to a yielding stud 9. Guides 10 and 11 aid in directing the letter to the printing

feed couple composed of the rollers 12 and 13 mounted on the shafts 14 and 15. Between 15 and 13 is the insulating bushing 16 which insulates the roll 13 from the body 5 of the machine, while the circumferential slot 17 (in which the brush 18 slides) forms suitable means for conveying current to the roller 13.

The brush 18 is slidably held against the 10 pressure of a spring 18^a in the tube 19 which is secured in the eye of a perpendicular stud 20 by means of a suitable set screw 21. This stud 20 is held on the bed plate 1 by the agency of a screw 22 which penetrates it after having passed through the insulating bushing 23.

The shaft 15 is shouldered at 15^a where it enters the yielding bearing bracket 24 and is slotted at its lower end to receive the universal coupling rod 25. A short shaft 26 with a slot in its upper end similar to that in 15 rotates in a fixed bearing in bed plate 2, being held against vertical movement by the shoulder 27 and the hub 28 of gear 29.

25 The bearing arm or bracket 24 is pivotally mounted on the under side of the bed plate 1 and is capable of movement on the stud 30 against the tension of the spring 31.

The shaft 14 which supports the roll 12 30 has suitable bearings in bed plates 1 and 2 and terminates in gear 32, from which it receives its motion. A collar 33 serves as a vertical support.

The printing couple is composed of the 35 impression roll 34 having a resilient periphery and a printing member 35, this latter member being adapted to engage frictionally the felt inking roller 36 which is designed to rotate loosely on the fixed stud 37. The 40 impression member revolves with its shaft 39 in the yielding bearing bracket 38, the shoulder 40, the coupling rod 42, the shaft 43 and the gear 44 performing the same functions as their counter-parts connected 45 with the roll 13. The bracket 45, however, serves as a vertical support for the shaft 43 in lieu of a collar or shoulder.

The printing member is carried by the 50 upper end of a magnetically jointed shaft, the driven portion 46 of which rotates in a fixed bearing in the bed plate 1 and in the bore of the clutch member 47. To this driven portion 46 and between its points of support, the detaining cam 49 and the clutch member 50 are fastened by means of appropriate set screws. The driving portion of 55 the clutch is cylindrical in shape, being provided with a hub 51 having a set screw 51^a by which the driving portion is secured to the shaft 52. The walls 53 and 54, together 60 with the sole 55, are integral with this hub and form a compartment for the reception of an appropriate winding for magnetizing this member. An insulated slip ring 56 encircles the outer circumference of the driver 65

and to this ring one end of the winding is connected, while the other end is connected metallically to the driver itself. The gear 57 fast on the shaft 52 communicates motion to the clutch driver and the thrust of the 70 whole is taken by the pivot screw 58 projecting through the bracket 59. A ball 60 intervenes between shafts 52 and 46 and the brush 61 pressing on the slip ring 56 carries current to the clutch. Brush holder stud 63 75 and brush sleeve 64 are similar to the equivalent parts of brush 18 and support the brush 61 and are themselves supported in the same way.

Stacker feed rolls 65 are mounted and rotated like rolls 12 and 13 (with the exception of neither being insulated from its shaft) and feed the letters into the stacker C beside the guide fence 67, from which they are crowded against the stacker back 68 by 80 means of the stacker cam 69.

Motion may be communicated to the machine by supplying power to any convenient spindle, the idle gears 70, 71, 72 and 73 contributing to form the train of gears necessary to put all parts in rotation.

The main release magnet 74 is a cylindrical coil of wire supported by the end pieces 75 and 76, piece 76 having a bifurcated hinge portion 77 by which the armature 78 95 and its detent 79 are supported. A pin 80 penetrates the eyes of 77 and a similar eye in 78 and permits movement of 78 thereon. Angular brackets 81 are screwed to 75 and 76 respectively, and secure 74 to the under 100 side of bed plate 1.

The auxiliary contact magnet 82 is similarly supported on the under side of bed plate 1 by the brackets 83, the end piece 84 serving as a hinged support for the contactor 85. The end piece 86 is bifurcated to form the prongs 87 which straddle the contactor 85 and aid it in making the long sweep when the magnet 82 is energized.

The detaining cam 49 has an irregular periphery in which the recess 83^a is formed. A hub 84^a integral with the cam and an eye 85^a penetrating the whole form the necessary means for attaching this member to the shaft 46.

110 The contact block 86^a with its associated blow-out magnet 87^a forms one of the links of the auxiliary operating means, which is located at some suitable location remote from the letter path. This block 86^a is held 115 between the fixed pivot 88 and the adjustable pivot 89 and a spiral spring 90 distended between the eyes 91 and 92, serves to hold it in longitudinal relation with the legs of the stirrup magnet 87^a. An insulating strip 120 93 occupies a portion of one side of the block 86^a at the end remote from the spring 90. The contact block and its concomitant parts are sustained on the under side of bed plate 1 by appropriate screws 97, the insu- 130

lation 98 interposing between the bed plate and the stirrup magnet 87^a. The free ends of 87^a are bent, as shown on the drawings, so that a magnetic field may be projected across 5 the point at which the contactor 85 ceases to engage block 86^a.

Part 99 is an adjustable stop for the armature 78 and part 100 is a fixed stop for contactor 85, while 101 and 102 are operating springs for 78 and 85.

The vital parts of this machine are electrically operated and current may be derived from any proper source. The drawings show it as being supplied from the battery 103, one terminal of which is connected to the body of the machine at point 104. The main release magnet 74 is energized by current which flows from 103 over the wires 105 and 106, around the winding of 74, leaving 15 by wire 107, and after passing over the stirrup 87, the block 86^a and the contactor 85 returns over the body of the machine to 104 and thence to the battery.

The clutch receives energy over the wires 25 105 and 108, the stud 63, the tube 64 and the brush 61, the return being over the body of the machine; while the magnet 82 is energized through the agency of the wires 105 and 109, the return being over the wire 110, 30 the tube 19, the brush 18, the insulated roll 13, the roll 12 and the body of the machine.

When the mechanism is to be operated, the parts are in the position shown in Fig. 1, the detent 79 engaging the notch 83^a of the 35 detent plate 49 and the magnet 82 (being energized) attracting the contactor 85. If no mail is passing, the printing wheel and its associated shaft with what members are attached thereto, is held stationary, although 40 there is a magnetic attraction between the driven clutch member 50 and the driving member composed of parts 53, 54 and 55.

When it is desired to cancel mail, the chute *a* is filled with a stack of letters and, 45 as each succeeding piece is fed forward by the feed roll 3, it passes between rolls 12 and 13, thus insulating them from each other. This action deenergizes the magnet 82 (which, as hereinbefore stated, has a subsidiary dampening electric circuit connection with the generating circuit and with the feed rolls 12 and 13) and allows the contactor 85 to be drawn back against the stop 109, during which operation it wipes 50 against the face of the block 86, thus closing the circuit on the magnet 74, causing it to attract its armature 78 and withdrawing the detent 79 from the detent cam 49. The printing member is then free to rotate and 55 is driven by the magnetic attraction that exists between the driven member 50 and the continuously rotating member attached to the shaft 52.

After each letter passes from between 60 rolls 12 and 13, the circuit of magnet 82 is

again reestablished and the contactor 85 is attracted. In resuming its former position, however, 85 does not close the circuit of magnet 74 as it wipes against the insulating strip 98.

70

This same cycle of operations is performed on each letter until the whole of the stack is canceled.

In the description of the general operation of the machine, the structure shown in 75 Figs. 1 and 2 has been adhered to, but the preferable construction is that shown in Figs. 11, 12, 13, 14, and 15, and it is to this latter arrangement of parts that the more specific claims are drawn. Many of the 80 parts in Figs. 11, 12, 13, 14, and 15 are like (in construction if not in proportions) to their equivalents in Figs. 1 and 2. Similar characters of reference, therefore, designate these parts in all the figures.

85

The printing couple in Fig. 12 differs from that in Fig. 9 in that there is a slight variation of the clutch mechanism. The brackets 45 and 59 are also dispensed with and the collar 120 and hub 121 perform 90 their functions. The driven portion of the clutch is identical with that in Fig. 9, its parts being similarly designated. The driving portion, however, is slightly modified, the hollow cylinder 122 being integral with 95 the hub 121. The spool 123 (of some non-magnetic material) is made to fit within the cylinder and while carrying the winding 124 forms an appropriate bearing for the shaft 46. The collector ring 125 is secured 100 to the under side of the cylinder by any suitable means, an appropriate insulating strip 126 intervening. One end of the winding is connected to this ring while the other is grounded to the body of the clutch.

105

The detent 127 herein shown is made up of the bifurcated arm 128 which carries a roll 129 sustained by a pin 130. A spring 131 connected between the hook 132 and the stud 133 serves to hold the detent in engagement with the cam 49. Projecting downwardly from the upper bed plate 1 is a stud 136, on which the hollow rock shaft 134 swivelly rocks. Carried in any suitable manner by the hollow rock shaft adjacent 110 one end thereof is the detent arm 127 projecting in one direction. Supplied in any suitable manner on the rock shaft adjacent the other end thereof is the horn shaped trip lever 135, which extends or curves in a direction at right angles to the direction, in which the detent extends, and terminates in a position adjacent the bore of the trip magnet 137, so as to be struck by the plunger 141 of said magnet 137.

115

The trip magnet 137 is of the iron clad plunger type, the outer shell 138 and the caps 139 being of some magnetic material. A tube 140 protrudes from one end of the magnet and is a non-magnetic substance. It 120

125

125

acts as a guide and support for the movable plunger 141. A spring 142 connected to the end of the plunger holds it normally against the protuberance 143 and the tension on this spring can be varied by means of the screw 144. The trip magnet as a whole is supported by the bracket 145 on the lower bed-plate 2.

A differential winding (two coils whose magnetizing forces oppose each other) provides the operating force for 137, one terminal of one winding being connected to the battery 103 by the wire 146 and the other terminal of the same winding being connected to the body of the machine at the point 147. One lead of the opposed winding is joined to the battery by means of the wires 148 and 146 while the other lead is connected to the brush 18 by the wire 149.

When no mail is passing through the machine the circuits on both windings are closed and being opposed to each other no attracting force is exerted on the plunger 141, but, when a letter enters the supplementary feed rolls, the circuit of one winding is broken by the separation of the rolls 12 and 13. This leaves the other winding free to act and the plunger 141 is attracted hitting the trip lever 135 (which is constructed and arranged, as hereinbefore set forth, so as to be struck by the plunger 141) and disengaging the detent 127 from the cam 49 whereupon the clutch rotates the die-cylinder.

After the letter has passed the rolls 12 and 13 again contact, the open circuited winding is closed and the former conditions are restored to await the next letter.

When the rolls 12 and 13 are separated the self-inductance of the winding being in series with said rolls would under normal conditions cause sparking at the point where the rolls separate and the highly oxidizing properties of this spark would soon result in corrosion of the rolls. This, however, is avoided by the differential winding. Self-inductance is caused by the collapse of the magnetic field on a coil of wire; but in this invention there is no self-induction in the coil which is opened as its magnetic field is neutralized by that of the opposing coil. Consequently, there is no spark on the separation of the rolls 12 and 13 and they are kept free from corrosion.

In Figs. 13, 14 and 15 all the essential parts of the machine are the same as in other figures except as will be hereinafter pointed out.

The cam 49 is dispensed with as is also the magnet 139 and the battery 103. In place of 49 a roll 200 rotatable on the screw stud 201 is mounted on the driven member 122^a of the clutch and, when 122^a is at rest, the roll 200 engages the enlarged forward end of the detent 202. The detent 202 is

provided with a sleeve portion 204 by which it is secured to the under side of bed plate 1 by the screw stud 205. A spring 203 stretched between the stud 206 and the projection 207 serves to hold detent 202 normally in engagement with the roll 200.

The generator *g* is of the series type, the armature 208 revolving between the field poles 209. The shaft 210 supports this armature (together with its commutator 211) being journaled in the pillow blocks 212 which are secured to the bed plate 2 by appropriate screws 213. The field poles 209 are also secured to 2 by screws 214. Brushes 215 and 216 are identical in construction to brush 19, but brush 215 is insulated from bed plate 2 while brush 216 is not.

The upper field pole 209 has a bifurcated projecting arm 217 at right angles to it, while the lower pole 209 also has a right angular projection 218 directed upward. The object of this upwardly directed extension 218 is to concentrate the magnetic field in the vicinity of the trip armature 219. Between the upper and lower field poles 209 is the series field coil 220, its core being shown in dotted lines in Fig. 14.

The trip armature 219 is held in 217 by the pin 223 and has a tongue 221 engaging the forward end of a pawl link 222. The rear end of 222 is blended into a bifurcated eye by which it is joined to links 224 and 225 with the aid of the pin 226. An integral projection 227 extending upward contacts with the screw 228 which (passing through a threaded hole in the depending projection 229) is prevented from turning by a jam nut 230.

A forked protuberance 231 on the upper pole 209 receives the lower end of link 224, pin 232 retaining it therein. The upper end of 224 is a forked eye, which, after straddling the forward eye of link 225 and being itself straddled by the forked eye of link 222 is connected to 222 and 225 by the pin 226.

The rear end of 225 has also a forked eye by which it is connected to the detent 202 by the pin 233.

The series field coil 220 is connected to the brush 64 by the wire 234 and to the brush 215 by wire 235. A wire 236 runs from brush 215 to brush 19.

When no mail is passing, rolls 12 and 13 are together. The series field is then short-circuited and *g* will fail to generate; any current present tending to travel from brush 215 over wire 236 to brush 19, to roll 13, to roll 12, to the body of the machine and back to brush 216. The current thus avoids the field coil 220 and prevents *g* from building up.

When a letter is between 12 and 13, this short-circuit is opened at that point (the letter being an insulator) and *g* is then in

a status to build up; current leaving by brush 215, passing over the wire 235 around the coil 220 over the wire 234 to brush 64, to the clutch winding, to the body of the machine and back to brush 216.

The coil 220 being thus energized it intensifies the generating power of g and at the same time attracts the trip armature 219 (against the action of the spring 219^b connected to the stud 219^a) and whose tongue 221 pulling on the pawl 222 draws the set of links forward causing the detent 202 to liberate the driven member of the clutch. At the same time that 222 is being drawn forward, it is also being lifted by 227 pressing against 228 until when 221 has reached the limit of its movement 222 will be in a position to clear it and the spring 203 will return the detent and the links to their former position in time for the detent to arrest the driven clutch member after it has made one revolution.

The generator g may be driven by any suitable means. Fig. 13 shows it driven by a belt 250 and pulley 251.

The invention having been set forth, what is claimed as new and useful is:—

1. In a postmarking machine, a shaft comprising a driving portion and a driven portion, a printing member movable with the driven portion, a feed couple comprising separable rolls, means for retarding the driven portion, and a second means remote from the direct letter path of the machine and having coöperating connections with the rolls, which, when separated actuates the second means, which in turn has coöperating connections with and operates the retarding means causing the same to release the driven portion.

2. In a postmarking machine, a shaft comprising a driving portion and a driven portion adapted to be intermittently magnetically coupled, a printing member on the driven portion, a feed couple comprising separable feed rolls, means for retarding the driven portion, and a second means remote from the direct letter path of the machine and having coöperating connection with said rolls, which, when separated actuates the second means, which in turn has coöperating connections with and operates the retarding means for coupling and uncoupling the driving and driven portions.

3. In a postmarking machine, an intermittently operated revoluble printing member, means for retarding said printing member, means comprising a pair of separable feed rolls forming parts of the walls of the path of the mail, said rolls having connections with the retarding means, whereby when said rolls separate said retarding means are actuated through said connections to release and stop said printing member.

4. In a postmarking machine, a printing

couple comprising a printing member and an impression member, the printing member being revoluble, means for operating the printing member, means for retarding the same and including an electric circuit normally open, a second circuit normally closed, a feed couple in the second circuit comprising a pair of separable rolls, which when separated by a passing letter breaks or opens the first circuit, means actuated mechanically when the second circuit is broken designed to close the first circuit, thereby actuating the retarding means to release the printing member.

5. In a postmarking machine, a printing couple including a printing member, an electric circuit, a pair of separable feed rolls constituting a part of said circuit which rolls keep the circuit normally closed, another circuit, a device to retard the printing member, an element in the first circuit, means for mechanically actuating said element when the first circuit is opened, an oscillatory member in the second circuit contacted with by said element for closing the second circuit to actuate said device to release the printing member.

6. In a postmarking machine, a revoluble printing couple including a printing member, an electric circuit, a letter path comprising separable walls constituting a part of said circuit, the separation of the walls resulting in the opening of the circuit, and means mechanically actuated when the circuit is broken, and electro-mechanical mechanism operated by said last mentioned means for controlling the rotation of the printing member.

7. In a postmarking machine, a printing couple comprising a revoluble printing member, an electric circuit, a device in the circuit for retarding the printing member, an oscillatory element in said circuit, a second circuit, a letter path, a feed couple comprising separable feed members constituting the walls of said path, said feed members being in the second circuit and forming a part thereof, means normally controlled by the second circuit, spring means for the last means, the separation of the feed members of the letter path acting to break the second circuit, thereby allowing the spring means to actuate the first means to contact with the oscillatory element for closing the first circuit which actuates said device to release the printing member.

8. In a post marking machine, a normally opened electric circuit, a normally closed electric circuit having separable contact members therein and forming a part thereof, a printing couple including a printing member, means in the normally opened circuit for controlling said printing member, a mechanical device to be actuated to close the normally opened circuit for actu-

ating said means, and a spring tensioned mechanical element controlled by the normally closed circuit to contact with the first mentioned mechanical device, when said 5 closed circuit is broken by the separation of said contact members, thereby closing the first circuit and operating said means to effect the release of the printing member.

9. In a postmarking machine, a revoluble 10 printing couple, an electric circuit, a spring tensioned device in and forming a part of said circuit to retard the printing member of the printing couple, a second normally closed circuit, a feed couple forming a part 15 of said closed circuit comprising separable feed rolls, which when separated act to open the normally closed circuit, and means between the two circuits for closing the first circuit as a result of breaking the second 20 circuit to actuate said device to release the printing member.

10. In a postmarking machine, a printing couple including a retarded printing member, an attendant feed couple comprising 25 separable rolls, means for retarding the printing member, an operating device to actuate the printing member when the same is released, a normally opened circuit including means to actuate the retarding 30 means to release the printing member when the circuit is closed, a second normally closed circuit in which said separable rolls form a link, whereby the separation of said rolls act to open said closed circuit, and 35 means connecting the circuits, whereby, upon opening the closed circuit, the first circuit is closed to actuate the retarding means, thereby effecting the release of the printing member.

40 11. In a postmarking machine, a printing couple including a retarded printing member, an attendant feed couple comprising separable feed rolls, a generating device, a continuously established normally dormant 45 electric circuit including said generating device, means for retarding the printing member, and designed to be controlled by said established circuit, a subsidiary dampening circuit including said generating device and 50 said feed couple, the separation of said separable rolls designed for so manipulating said dampening circuit, as to render active, the continuously established circuit and cause said means to release said printing member.

55 12. In a postmarking machine, a revoluble printing couple, a feed couple comprising separable rolls, and means remote from the direct letter path when said rolls are separated 60 for controlling the rotation of said printing couple, means for retarding the printing member and designed to be actuated by the first means to release the printing member, said first means including two

circuits, one being normally open and de- 65 signed to control the second means, the other circuit being normally closed and including the separable rolls as a part thereof, the separation of such rolls acting to open the normally closed circuit, thereby result- 70 ing in closing the normally open circuit.

13. In a post marking machine; a printing couple including a printing member; means for retarding said member; two electric circuits, one being normally closed and 75 controlling the other, which is normally open and controls said means; separable electric connectors in the closed circuit, which when separated opens the closed circuit, which results in closing the open circuit to operate the means to release the printing member.

14. In a post marking machine; a printing couple including a printing member; a device for retarding said member; dual 85 means, one being in operation, but inactive, the other being dormant but adapted for controlling said device, means whereby the former controls the latter; and a pair of separable parts, which, when separated, 90 causes the former to so control the latter, rendering it active, whereby the latter operates the device to release the printing member.

15. In a postmarking machine, a revolu- 95 ble printing member, a detent retarding the same, a pair of electric circuits having connections and one being closed normally and the other normally open, and a pair of members in the closed circuit separable by the 100 mail matter opening the closed circuit to close the open circuit through said connections, the closing of the open circuit actuating the detent to release the printing member.

16. In a postmarking machine, a revolu- 105 ble printing member, a detent retarding the same and having an armature, spring means therefor, a pair of circuits having intermediate mechanical connections, one circuit 110 being normally closed and the other normally open, a magnet in said open circuit, a pair of separable feed members in the normally closed circuit adapted to be separated by the mail matter opening the closed 115 circuit, which closes the open circuit through said connections energizing the magnet and attracting the armature to release the detent of the printing member.

17. In a post marking machine, a revolu- 120 ble printing couple, a detent for the printing member thereof, separable feed rolls for the couple, and means of connection between the feed rolls and the detent, whereby as the feed rolls are separated the detent is actuated to release the printing member of the printing couple.

18. In a post marking machine, a revolu-

ble printing member, a detent retarding the same, a pair of feed rolls for the printing member, and electrical connections between the feed rolls and the detent, whereby as 5 the feed rolls are separated the detent is actuated to release said printing member.

19. In a post marking machine, a revolvable printing member, a detent retarding the same, a pair of feed rolls for the printing member, and combined electrical and mechanical connections between the feed rolls and the detent, whereby as the feed rolls are separated the detent is actuated to release said printing member.

15 20. In a post marking machine, a printing couple, means for retarding the printing member thereof and including an electric circuit normally opened so that the retarding means holds the printing member, a normally closed circuit, a feeding couple comprising separable rolls in said closed circuit and forming a link therein, and connections between said circuits, whereby the separation of said rolls opens their circuit, and 25 closes the first circuit through said connections, thereby actuating the retarding means to effect the release of the printing member.

21. In a post marking machine, a printing couple, means for retarding the printing member thereof and including an electric circuit normally opened so that the retarding means holds the printing member, a normally closed circuit, a feeding couple comprising separable rolls in said closed circuit and forming a link therein, and elements remote from the letter path and adapted to connect said circuits, whereby the separation of said rolls opens their circuit and closes the first circuit through said 35 elements, thereby actuating the retarding means to effect the release of the printing member.

22. In a printing machine, an electric circuit normally opened including a revolvable printing couple therein, means normally controlled by said normally opened circuit for retarding the printing member of the printing couple, a second electric circuit normally closed, a feed couple comprising 45 separable rolls in said closed circuit and forming a link therein, a device remote from the letter path and in said open circuit, a contact member held out of contact with said device by the second circuit, whereby the separation of the rolls opens the second circuit allowing the release of said contact member, and means to move said contact member to engage with said device to close the first circuit to actuate the retarding means whereby the release of the printing member is effected.

23. In a post marking machine, a revolvable printing couple, an electric circuit normally opened in which the printing member

of the couple is included as a link in said circuit, means controlled by said normally opened circuit for retarding the printing member of the printing couple, a second electric circuit normally closed including a feed couple therein comprising separable rolls, 50 a contact member controlled by the second circuit, the first circuit including a device remote from the letter path, the separation of the feed rolls resulting in opening the second circuit, mechanical means for causing said contact member to contact with said device to close the first circuit, to actuate the retarding means to release the printing member.

24. In a post marking machine, a revolvable printing couple, an electric circuit normally opened, in which the printing member of the couple is included as a link in said circuit, means controlled by said normally opened circuit for retarding the printing 80 member of the printing couple, a second electric circuit normally closed including a feed couple therein comprising separable rolls, a contact member controlled by the second circuit, the first circuit including a 85 device remote from the letter path, the separation of the feed rolls resulting in opening the second circuit, mechanism for causing said contact member to contact with said device to close the first circuit, to actuate the 90 retarding means to release the printing member, and spring means to return the retarding means to its normal position when the first circuit is restored to its normal 95 open condition.

25. In a post marking machine, a revolvable printing couple, means for retarding the printing member thereof, separable forwarding means, and connections between the separable means and the retarding means, 105 whereby as the separable means separate, the retarding means act to release the printing member.

26. In a post marking machine, a revolvable printing couple, inter-dependent electric circuits, means in one circuit for retarding the printing member of said couple, forwarding means forming a link in and adapted to make and break the other circuit, and connections between said circuits, where- 110 by upon breaking of the forwarding means circuit, the other circuit is established, thereby actuating said retarding means to effect the release of the printing member.

27. In a post marking machine, a revolvable printing couple, retarding means for the printing member thereof, an electric normally opened circuit adapted for controlling the retarding means, a second electric circuit having connections with the first circuit, a 120 pair of separable feed members constituting a part of the second circuit, whereby upon the separation of the feed members, the

second circuit is opened, thereby resulting in closing the first circuit which actuates the retarding means to release the printing member for rotation.

5 28. In a post marking machine, a revolute printing couple, means for retarding the printing member thereof, and separable forwarding means having electrical and mechanical connections with the retarding means, whereby as the separable means separate the retarding means act to release the printing member.

10 29. In a post marking machine; a printing couple including a printing member; means to retard said printing member; separable means; dual mechanisms, one being controlled by the separable means, the other controlling said retarding means; means whereby the former of said dual mechanisms 20 controls the latter of said mechanisms, so when the separable means separate, the latter actuates the retarding means to release the printing member.

15 30. In a post marking machine; a revolute printing couple; retarding means for the printing member thereof; separable means; dual connections, one controlling said retarding means, the other being controlled by the separable means; and a device remote from the letter path, whereby the former of said dual connections is controlled by the latter, so when the separable means separate, the former actuates the retarding means to release the printing member.

25 31. In a post marking machine, a revolute printing couple, means for retarding the printing member thereof, separable forwarding means, elements coördinately actuated by the separation of the separable means to operate the retarding means whereby the release of the printing member is effected.

30 32. In a post marking machine, a revolute printing couple, means for retarding the printing member thereof, separably forwarding means, elements coördinately actuated by the separation of the separable means to operate the retarding means to 50 effect the release of the printing member, said elements in themselves again being coördinately actuated to cause the restoration

of the retarding means to position, whereby the retardation of the printing means is effected.

55 33. In a post marking machine, a revolute printing couple, a detaining and releasing device for the printing member thereof, forwarding means, and means connecting said forwarding means and the device, whereby upon substantially uniform operation of said forwarding means the printing member is released and detained intermittently.

60 34. In a post marking machine, the combination of an impression roller and a printing member coöperable therewith, of a detaining and releasing device therefor, forwarding means operable substantially synchronously and uniformly, and means connecting the said forwarding means and the device, whereby upon such operation of said forwarding means, the alternate release and retardation of the printing member is effected.

65 35. In combination, an impression roller, a printing member coöperable therewith, a detaining and releasing device therefor, forwarding means operable synchronously and uniformly, and electrical means connecting 80 said forwarding means and the device, whereby upon such operation of said forwarding means the alternate release and retardation of the printing member is effected.

70 36. In combination, an impression roller, a printing member coöperable therewith, detaining and releasing means therefor, opposed forwarding members operable substantially synchronously and uniformly, and electrical means connecting 90 said opposed forwarding members and the detaining and releasing means, whereby upon such operation of said forwarding members the alternate release and retardation of the printing member is effected.

75 In witness whereof, the applicant's signature, is hereunto affixed in the presence of two witnesses.

ROBERT A. BOSWELL.
